REFRIGERATING APPARATUS

Lawrence A. Philipp, Detroit, Mich., assignor to
 Nash-Kelvinator Corporation, Detroit, Mich., a
 corporation of Maryland

Application October 24, 1947, Serial No. 781,957

7 Claims. (Cl. 20—35)

1

This invention relates generally to refrigerators and more particularly to composite refrigerator cabinet panels.

One of the objects of the present invention is to provide an improved refrigerator cabinet panel of composite construction.

Another object of the invention is to provide an improved composite refrigerator door to decrease heat conduction between an outer door casing and an inner door panel.

Another object of the invention is to provide an improved composite refrigerator cabinet panel of decreased heat conducting qualities which is inexpensive to manufacture.

Further objects and advantages of the present invention will be apparent from the following description, reference being had to the accompanying drawings, wherein a preferred form of the present invention is clearly shown.

In the drawings:

Fig. 1 is a front view of a refrigerator including a cabinet shown with an access door open, embodying features of my invention;

Fig. 2 is an enlarged fragmentary sectional view of the refrigerator door, taken along the line 2—2 of Fig. 1;

Fig. 3 is a fragmentary view partly in elevation and partly in section of the door, taken along the line 3—3 of Fig. 2; and

Fig. 4 is a sectional view of a rear panel of the door, shown removed therefrom.

In the drawings, there is shown a refrigerator having a cabinet, designated generally by the numeral 20. The cabinet 20 has a food storage compartment 22 which may be cooled by a refrigerant evaporator of any suitable type; the present evaporator having an ice making compartment closed at the front thereof by an interior door 24. The front of the cabinet has an access opening to compartment 22 which is closed by an outer or main access door 26 which may be hinged to one side of the cabinet 20.

The door 26 comprises, in general, an outer metal casing 28 and an inner or rear composite panel 30. The composite panel 30 closes the back of the metal door casing 28 forming therewith a hollow door structure or shell. Heat insulation 32 of any suitable type is preferably provided in the hollow door structure to decrease heat leakage through the door into the cabinet interior.

The door casing 28 may be made of thin sheet steel formed in general dish-like shape having a rear, inturned reinforcing flange 34. This flange 34 preferably extends along the casing top, sides and bottom and is preferably reinforced by bending inwardly, a marginal flange portion 36 thereof. Attached to the casing flange 34 is a continuous gasket 38 arranged to engage the

2

outer surface, as at 40, of the front of the cabinet around the cabinet access opening to form a seal. In general, the gasket 38 comprises a base 42 and a lip or bumper portion 44. The gasket base 42 and the bumper portion 44 are joined together in a manner to form a channel which faces inwardly to receive an outer marginal portion of the composite panel 30. This gasket 38 may be made of rubber or of any other suitable material.

10 In accordance with my invention I make the composite rear panel 30 of a central panel member 46 and an outer panel extension or heat breaker strip 48. The panel 46 is preferably made of a light weight sheet material, such as inexpensive sheet steel and the size of the panel 46 is made such that its peripheral edge terminates in spaced relation to and inwardly of the casing flange portion 36 so as to decrease heat conduction therebetween. The panel extension member 48 is made of a low heat conductive material, such as fiber board. This panel extension member 48 extends preferably around the entire periphery of the panel 46 in the manner of a frame to provide a good heat break between the panel and the surrounding casing flange 34. The panel 46 and its peripheral extension member 48 are united or cemented together in flat overlapping relationship preferably by rubber cement, under the application of pressure. Preferably, the overlapping portion of the panel 46 is offset inwardly, as at 47, so that the outer surfaces of the panel member 46 and of its extension member 48 are flush or coplanar. Cemented to the exterior, flush surfaces of the panel 46 and its extension 48 is a finish covering 54, preferably a thin sheet of plastic material. This plastic sheet 54 covers the joints between the panel 46 and panel extension 48. The plastic cover sheet 54 is cemented to the panel 46 and panel extension 48 preferably by rubber cement and preferably under the application of heat. Prior to the cementing of the panel member 46 and panel extension together, the panel 46 is preferably formed, as at 56, to provide a bead, giving added rigidity to the panel, and at the same time may be formed to provide the offset flange 47. The stiffening bead 56 is preferably continuous, extending along and in spaced relation to the sides, top and bottom edges of the panel 46. When the outer plastic covering 54 is cemented under pressure to the panel member, the plastic covering is pressed to take the form of the bead and of the flange 47; the plastic covering being set to fit complementary with the panel formations. When the door is assembled, an outer marginal portion of panel extension and the plastic cover sheet are received in the channel of the rubber gasket 38, spacing the metal panel member 46 from the metal casing

28. Spaced, spring fasteners 58 or other suitable means may be provided for attaching the gasket 38 and composite panel to the casing flange 34. Aligning apertures may be provided in the casing flange 34, panel extension and in the cover 54 to receive the fastening 58. The cover sheet 54 need not extend entirely to the outer edges of the panel extension 48, but instead may terminate inwardly of the fasteners.

For use in household refrigerators inexpensive hot rolled sheet steel of approximately twenty thousandths thickness may be used to form the member 46 and the sheet 54 may be formed of plastic approximately ten thousandths in thickness. These sheets may be united by any suitable cement and pressed together and in some instances when certain types of cement are used it may be desirable to apply heat during the pressing operation.

Since the members 46 and 54 are united to the frame of fibre board 48 and the board 48 secured to the casing 28 a rigid door construction is provided. This is accomplished by inexpensive sheet steel without requiring any form of corrosive preventing coating such as rust proofing or coating of vitreous enamel because the plastic member 54 protects the member 46 from moisture present in the refrigerator while the insulating fibre board provides a breaker strip between the metal member 46 and the casing 28.

In the interior of refrigerators certain amount of moisture tends to form on the inner walls and some moisture may form on the plastic member 54. Some of such moisture is absorbed in the plastic member tending to cause the member 54 to expand. Such expansion is eliminated by the sheet metal member 46 being united to the member 54. In view of the fact that member 54 cannot expand it can be secured to the casing 28 to aid in forming a rigid door whereas if the member 54 should be allowed to expand while being secured to the casing 28 the member 54 would buckle and in some instances buckle inwardly and tend to engage objects stored in the refrigerator.

From the foregoing description, it will be noted that I have provided an improved door construction to decrease heat conduction between inner and outer parts of the door. It will also be noted that I have provided an improved refrigerator panel of composite construction in which the door panel and its outer finish cover are cemented together and to a marginal panel extension member or breaker strip to decrease heat conduction and also decrease cost of manufacturing refrigerator cabinet panels.

Although only a preferred form of the invention has been illustrated, and that form described in detail, it will be apparent to those skilled in the art that various modifications may be made therein without departing from the spirit of the invention or from the scope of the appended claims.

I claim:

1. A composite refrigerator panel comprising, a panel member of sheet material, a panel extension member of low heat conductive material extending outwardly of the periphery of said panel member and forming a joint therewith, and a sheet of plastic material cemented flat against and to corresponding surfaces of said panel member and of said extension member overlying said joint.

2. A composite refrigerator cabinet panel comprising, a sheet metal panel member, a panel

extension member of low heat conductive material extending outwardly from the periphery of said panel member, a cementitious material cementing said panel member and said extension member together and sealing the joint therebetween, and a sheet of plastic material cemented to corresponding surfaces of said panel member and said extension member further sealing said joint.

3. A composite refrigerator cabinet panel comprising, an inner metal panel member, an outer heat breaker strip extending along the periphery of said metal panel member, means securing said metal panel member and said heat breaker strip together, and a sheet of plastic material cemented to and flat against corresponding surfaces of said metallic panel member and said breaker strip.

4. A composite refrigerator cabinet panel comprising, an inner metal panel member, an outer heat breaker strip extending along the periphery of said metal panel member, means securing said metal panel member and said heat breaker strip together, a sheet of plastic material cemented to and flat against corresponding surfaces of said metallic panel member and said breaker strip, and complementary stiffening deformations in said inner metal panel and in said sheet of plastic material inwardly of said breaker strip.

5. A composite refrigerator cabinet door comprising, an outer casing having an inturned flange, a rear panel member having an outer peripheral edge spaced inwardly from said inturned flange, a heat insulating member overlapping said inturned flange and overlapping a marginal edge portion of said inner panel closing the joint therebetween, and an outer cover member covering the outer surfaces of said rear panel and said heat insulating member.

6. A composite refrigerator cabinet door comprising, an outer casing having an inturned flange, a rear panel member having its outer peripheral edge spaced inwardly from said inturned flange, a connecting member of low heat conducting material overlapping adjacent portions of said flanges closing the space therebetween, and a plastic covering on the outer surfaces of said rear panel and of said connecting member.

7. A composite refrigerator cabinet door comprising, an outer sheet metal casing having a rear inturned flange, a rear panel member having an outer peripheral edge spaced from said inturned flange, a plastic breaker strip overlapping said inturned flange and said inner panel closing the space therebetween, means attaching said rear panel and said breaker strip together, a gasket attached to said inturned flange having an inwardly facing channel receiving an outer portion of said breaker strip, a fastener connecting said gasket and said breaker strip to said inturned flange, and a covering on the outer surface of said rear panel and on the outer surface of said breaker strip covering the joint therebetween.
